UNITED STATES PATENT OFFICE.

ELMER C. DITTMAR, OF WILLIAMSPORT, PENNSYLVANIA, ASSIGNOR TO THE CROMAR COMPANY, OF WILLIAMSPORT, PENNSYLVANIA, A CORPORATION OF PENNSYLVANIA.

MACHINE FOR FINISHING FLOORING.

Application filed September 14, 1921. Serial No. 500,661.

This invention relates to certain new and useful improvements in machines for finishing flooring and more particularly to means for applying a coating of wax to the finished strip of flooring and a coating of waterproofing compound to the unfinished face of the strip, the object being to provide a machine which is so constructed that a strip of flooring can be set in motion and while in motion the opposite faces of the strip can be coated so as to polish one face and apply a coating of preservative to the other face.

Another object of the invention is to provide a machine in which a block of solid wax is fed against a rotary applying device so that when said device passes over the finished face of the strip of lumber to be waxed, the wax will be applied and rubbed in at the same time.

Another and further object of the invention is to provide a machine which is exceedingly simple and cheap in construction and one in which wax is fed automatically to the applying brush in such a manner that the proper amount of wax will be applied at all times so as to wax the varnished face of the strip in its passage therethrough.

Another and further object of the invention is to provide novel means for applying oil or preservative liquid to the unfinished face of the strip so that the entire surface of the strip will be protected against moisture.

Other and further objects and advantages of the invention will be hereinafter set forth and the novel features thereof defined by the appended claims.

In the drawings,

Figure 1 is a side elevation of a machine constructed in accordance with my invention;

Figure 2 is a top plan with the cover of the waxing device removed;

Figure 3 is a detail section through the waxing device showing the automatic means for driving the same;

Figure 4 is a detail section showing the manner of mounting the rotary members to allow the same to be adjusted in respect to the face of the strip in its passage through the machine; and

Figure 5 is a detail section through the fountain brush used for applying the oil to the unfinished surface of the strip.

In the drawings 1 indicates a frame provided with standards 2 supporting the guide way 3 which is provided with a feeding throat 4 in which the strip to be finished is forced. The strip is adapted to be continuously moved through the guide way 3 by any suitable feeding mechanism and I have shown a pair of feed rollers 5 for this purpose, but it is, of course, understood that I do not wish to limit myself to the use of feed rollers as I am aware that other feeding mechanism can be employed, such as a chain feeding device, without departing from the spirit of my invention.

The top of the frame is provided with suitable guide ways 6, 7 and 8 in which are slidably mounted movable supports 9, 10 and 11 which are operated by screws 9', 10' and 11' so that the supports can be adjusted into any position desired for the purpose hereinafter fully described. Mounted on the connecting members forming the guide way is a housing 12 provided with slots in its bottom through which extends shafts 13 and 14 which are mounted in the movable supports 9 and 10 and are provided with beveled gears at their lower end.

In Figure 4 I have shown a detailed section illustrating the manner of driving the shafts 13 and 14 and as the constructions employed for driving both shafts are identical, the description of one will be sufficient for both. The shaft 14 carries a beveled gear 15 which meshes with a beveled gear 16 feathered on a driving shaft 17 which is driven from any suitable drive shaft of the machine and the particular manner of driving this shaft is immaterial.

The beveled gear 16 is provided with a collar 18 which is embraced by a forked arm 19 carried by a bearing 20 fixed on the movable support 11 so that as the movable support 11 is adjusted within its guide way, the beveled gears 15 and 16 will be held in mesh.

As the movable support travels in its guide way, the beveled gear 16 slides on its shaft so as to hold the gears in mesh. The housing 12 is provided with a division plate 21 and mounted on the shaft 13 is a brush 22 and mounted on the shaft 14 is a brush 23. The shafts 13 and 14 are driven in opposite direction so that the brush 22 rotates in a direction opposite to the movement of the material passing through the

machine while the brush 23 rotates in the direction of the movement of the material passing through the machine.

In the drawing I have shown the brushes 22 and 23 formed with bristles and I have found that very good results can be obtained by using rotating brushes employing bristles and I have also found that devices of this kind can be used with brushes formed of 10 felt, fiber or other material and therefore I do not wish to limit myself to the use of bristle brushes. The brush 23 forms an applying brush while the brush 22 forms a polishing brush.

15 Extending diagonally from the housing 12 is a trough 24 in which is adapted to be placed a cake of wax 25 which is engaged by the follower 26 having a pivoted member 27 mounted on the outer end thereof provided 20 with a notch 28 adapted to receive one of the squared ends of a feed screw 30.

The feed screw passes through the threaded bore of a hub 31 of a worm gear 32 which meshes with a worm 33 mounted on a 25 shaft 34 arranged at right angles to the feed screw. The shaft 34 carries a worm gear 35 which meshes with a worm 36 carried by a vertical shaft 37 provided with a gear 38 adapted to mesh with the gear of one of the 30 driven shafts of the machine and through the medium of the worms and worm gear, the speed is reduced so that the screw travels slowly in order to force the wax against the edge of the brush so that the brush will 35 apply the same to the surface of the strip.

As the shaft carrying the brush is adjustably mounted, the brush can be adjusted in respect to the face of the strip so that proper tension will be obtained in order to 40 apply the wax thoroughly.

The hub 31 is carried by a removable member 39 held in position by pivoted locking member 40 and by swinging the locking member out of the path of the movable 45 member 39, the movable member can be raised vertically as to remove the worm 32 and the feed screw.

By forming the feed screw with squared ends as shown at 29, after the screw has 50 reached its limit of travel, the member 39 is raised vertically out of its support, it of course being understood that the pivoted member 28 is swung upward into vertical position and off the squared end. The member is then reversed and placed back into 55 its position so that additional cakes of wax can be placed therein in order to feed the same against the brush. This prevents the turning back of the screw when inserting 60 new cakes of wax and provides a construction which is very simple.

The trough 24 and housing 12 are closed by a cover 41 and the movable member 9 slides in a guide way 42 formed in the support 65 43 as clearly shown in Figure 1.

As the strip of material is fed through the machine by the feeding mechanism, the power used for driving the feeding mechanism drives the gear 38 and the shafts 13 and 14 through the medium of the gears so 70 that the shafts 13 and 14 are rotated in opposite directions. As the cake of wax is held in contact with the edge of the brush, the wax is picked up by the brush and carried upon the face of the strip, so as to 75 apply an even coating thereto. The waxed face of the strip then comes in contact with the brush 22 which is rotated in an opposite direction which removes any surplus of wax and polishes the surface so that when the 80 strip leaves the machine its face is waxed and polished.

In using a machine of this kind I have found that in different seasons of the year it may be necessary to employ threads of 85 different sizes for the feed thread so that in hot weather a slower feed can be obtained than in cold weather and therefore I do not wish to limit myself to the particular construction of feeding mechanism herein shown and described as my invention consists in automatically feeding a cake of wax to the edge of a brush through the medium of gears so that the proper amount of wax will be fed to the brush at all times to avoid 95 applying too heavy a coating to the surface being waxed.

In the drawing I have shown a burnishing device 44 mounted on the movable support 11 composed of a coil spring having a series of glass burnishers disposed between the convolutions of the spring for burnishing the varnished surface of the strip before it reaches the waxing brush, the particular construction of burnishing device being shown and described in a companion application filed September 14, 1921, Serial No. 500,659.

In order to produce a prefinished flooring so that the same can be prefinished in the 100 factory and shipped to the purchaser in condition to be laid without further treatment, I have found that it is necessary to coat the entire surface of a strip and in order to accomplish this result I arrange a fountain brush 45 opposite the polishing brush 22, which brush is composed of a nozzle having a pad 46 disposed therein which pad can be formed of any suitable material, such as felt, bristles, leather, fiber or other material of similar nature. The brush is provided with an opening 47 from which leads a pipe 48 having an upturned portion terminating in a hopper 49, into which is adapted to be fed a waterproofing composition from tank 50 herein shown provided with a valve controlled spout 51 controlling the supply of fluid delivered to the receiving hopper.

110 In the machine now in use I employ an 130

oil for a waterproofing compound and in use the tank is filled with oil and the valve 51 adjusted so that the proper amount of oil will pass from the tank into the receiving hopper from which it is fed by gravity into the fountain brush, which is provided with a handle 52 adjustably mounted in a support 53 so that the same can be adjusted in respect to the unfinished face of the strip.

10 The brush is adjusted so that the pad is in contact with the unfinished side of the strip of flooring and as the strip passes the fountain brush oil is applied to the face thereof and I have also found that in devices 15 of this kind in use there is a certain amount of leakage which allows the oil to run over the edges of the strip so that the entire unfinished surface of the strip will be coated with oil to prevent the strip from absorbing 20 moisture in shipment.

From the foregoing description it will be seen that I have provided a machine having a guide way in which a strip is propelled past a wax applying brush and then a polishing brush so that the varnished face of the strip is waxed and polished and as the strip moves in the guide way, it passes the fountain brush so that the coating of oil is applied to the opposite faces thereof. The 25 strip is then delivered from the opposite end of the machine and after drying is ready for shipment.

I am aware that I have shown certain details of construction that are not essential 30 in carrying out my invention and I do not wish to limit myself to these details as my invention consists in providing means for continuously moving and guiding a strip in a defined path past a pair of brushes and a 35 fountain brush in connection with means for supplying the fountain brush with oil and one of the rotary brushes with wax so that one surface of the strip will be waxed and polished and the other coated.

40 While in the specification I have described the operation of the oiler and waxer as a joint operation I am aware that either one can be used separately without the other so as to apply either a coating of wax or a 45 coating of oil to the face of a strip of lumber and therefore I do not wish to limit myself to the use of the machine for finishing a previously varnished strip of lumber as the same can be used for applying a coat of 50 wax to a strip of lumber which has not been prefinished without departing from the 55 spirit of my invention.

What I claim is:—

1. The combination with an apparatus 60 having means for moving and guiding a series of strips of previously varnished lumber with their ends in engagement with one another, of a rotary wax applying device adjustably mounted in respect to the var- 65 nished face of the strips in their passage

therethrough, a trough for holding a block of wax, means for continuously feeding said wax against the rotary applying device, and a polishing brush arranged in advance of said wax applying brush adapted to engage 70 the waxed face of said strips in their passage therethrough, said last mentioned brush rotating in the direction opposite to the movement of the strips for polishing the wax applied. 75

2. A machine for applying wax to strips of previously varnished lumber having means for continuously moving and guiding a series of strips of lumber with their ends in engagement with one another, a rotary 80 brush adjustably mounted in respect to the moving strips of lumber and adapted to rotate in the direction of movement of said strips in their passage therethrough, means for feeding wax to said brush and a polishing brush rotating in the opposite direction to the movement of said strips arranged to engage the face of said strips for polishing the wax applied. 85

3. In a machine of the kind described, the 90 combination with a wax tray having a follower mounted therein provided with a socket, of a cap member provided with a worm wheel having a threaded bore, a feed screw working in the threaded bore of said 95 worm wheel having a square end adapted to extend into the socket of said follower, said cap member being detachably mounted to allow the screw to be reversed after it has reached its limit. 100

4. In a machine of the kind described, the combination with a wax tray having a follower movably mounted therein provided with a movably mounted socket, of a continuously rotating shaft having a worm fixed 105 thereon, a detachable cap member carrying a worm wheel meshing with said worm, said worm wheel having a hub provided with a threaded bore and a feed screw working in said threaded bore having squared ends 110 adapted to fit within the movable socket of said follower for moving said follower in said tray.

5. An apparatus having a guide way for supporting and guiding a strip of lumber on edge, means for propelling said strip in said guide way, a brush rotating in the direction of travel of said strip arranged to engage one face thereof, a brush rotating in a reverse direction to the path of travel of said strip arranged to engage the face of said strip, means for supplying the first mentioned brush with wax and means for coating the opposite face of said strip in its passage through said machine. 115 120

6. An apparatus having means for guiding and continuously moving a previously varnished strip of lumber on edge in its passage therethrough, a rotary brush arranged to engage the varnished face of said 125 130

strip for applying wax thereto, said brush rotating in the direction of travel of said strip, a polishing brush rotating in the opposite direction to the movement of the strip for polishing the waxed face of said strip and independent means for adjusting said brushes.

7. An apparatus having means for continuously moving and guiding a strip of lumber in a defined path, a series of burnishers

arranged to engage one face of said strip in its movement through said machine, a rotary brush for applying a coating of wax to the face of said strip and a rotary polishing brush arranged to engage the waxed face 15 of said strip for polishing said strip in its passage through said machine.

In testimony whereof I hereunto affix my signature.

ELMER C. DITTMAR.
